COMBINATION CABANA AND SOLARIUM
THEREFOR

Mike Tecton, 5101 45th St. NW,
Washington, D.C. 20016

Filed Oct. 24, 1965, Ser. No. 87,909

Term of patent 14 years

(Cl. D83—1)

FIG. 1 is a perspective view of a combination cabana and solarium therefor, embodying my new design,

FIG. 2 is a top plan view thereof,

FIG. 3 is a right side elevational view thereof,

FIG. 4 is a rear elevational view thereof.

I claim:

The ornamental design for a combination cabana and solarium therefor, substantially as shown.
